C. VASTIK ET AL

ELECTRICALLY DRIVEN PHONOGRAPH DRIVING MECHANISM

Filed August 3, 1925

Fig.1

UNITED STATES PATENT OFFICE.

CHARLES VASTIK AND MICHAEL BROZOVICH, OF BINGHAMTON, NEW YORK.

ELECTRICALLY-DRIVEN-PHONOGRAPH DRIVING MECHANISM.

Application filed August 3, 1925. Serial No. 47,854.

Our invention relates to an electrically driven phonographic driving mechanism, and record turntable, which operates comparatively noiselessly, needs little lubrication and having means electrically applied to variably control and regulate the speed of the turn table rotations for a sound record, and to automatically stop said rotations and shut off the electric current when the 5 needle has completed its course on the record, for the production of the tones intended. With these objects in view our invention consists of certain novel features of construction and arrangement of parts as will be 10 15 hereinafter more fully described and pointed out in the claims, reference being had to the accompanying drawings, in which Fig. 1 is a side view of our device.

Fig. 2 is a plan view of our device with 20 parts broken away.

Fig. 3 is a side view of a part of our device.

Fig. 4 is a diagrammatic view of the wiring plan of our device.

25 The same reference characters denote like parts in each of the several figures of the drawings.

In carrying out our invention, we have the usual motor board A, to which the driving mechanism is attached as shown in Fig. 30 1. The motor board is adapted to be removably mounted in a casing or housing E of a phonograph, as shown in Fig. 1. Our improved driving and controlling mechanism 35 is partly mounted on the under side of the board and partly located on the upper side of the board, and the record turn table 3 is on the upper side of board A. The driving mechanism consists of a suitable supporting 40 frame B, which may be attached or mounted by means of screws or other means of connection on the under side of the board. The supporting frame B may be of any convenient form for use. Mounted in the motor 45 board A and supported in the frame B we have the usual turntable shaft 2, on which is mounted the record turntable 3; on the shaft 2 we have mounted, below the board, A, a disk 4 which may or may not have a beveled surface 5; pivotally mounted within the frame B we have an electric motor

C. We preferably employ an electric motor which is adaptable to either a direct or alternating current. We support the motor C as follows: Around the body we may have 55 mounted a metal band 6 or other means of support, having the projecting lugs 7, 7 with which a lug 8 on frame B pivotally engages by means of the pivot 9; on shaft 10 of the motor C we have a friction gear 11, which 60 engages the surface 5 of the disk 4, as shown in Fig. 1; to form a resilient contact between the gear 11 and the surface 5 of the disk, we have the coil spring 12, mounted in any 65 convenient manner and having connection with the motor C and the frame B; the device is operated in connection with the usual tone arm and needle. As a further part of our device we have attached to the board A in any convenient manner a rheostat D and 70 connected with it an operative button 15, which may be positioned for operative convenience either above board A or on the side of casing E; we elect to position the various 75 parts of our invention, relatively to each other, as, in practical use and construction, may be hereafter dictated, without departing from the spirit and purpose of our invention. The button 15 controls the movement 80 of the contact arm of the rheostat, for the operation of the same. As a further part of our invention we have mounted on board A a combined automatic stop and current cut off F; the stop and cut off structure is as follows; We have a metal frame support 85 consisting of plate 15 of any convenient form, and mounted horizontally and pivotally on plate 15 we have the lever stop arm 16, on which arm is mounted stop projection 16^a, the arm also having pivotally mounted on 90 the inner end thereof the link 18, having connection with pawl 19; also connecting with the stop arm 16 we have the coil spring 20; also pivotally mounted on F we have the 95 brake and control handle 21, pivoted at 21', on which is mounted felt brake 22; on the inner end of handle 21 we have ratchet tooth 24, engaging pawl 19. Mounted in any convenient manner on board A we have a switch box E; and mounted pivotally on control 100 handle 21 we have the rod 26 extending slidably into switch box G, and having on its in-

ner end the head 27; mounted within box G we have the flat spring 27, having mounted thereon the button 29 and contact point 30; also mounted in box G we have the flat 5 spring 31, having thereon the contact point 32, adapted to contact with point 30. Pivotally mounted on frame B, by pivot *a* we have a support H having the horizontal arm 33 and the vertical arm 34, and having on 10 the curved end of arm 33 the bearing 35 and in arm 34 the bearing 36; mounted in bearings 35 and 36 we have the shaft 37, on which is mounted a governor 38, gear 39 and disk 40; gear 39 having frictional contact 15 with face 5 of disk 4; mounted between arm 33 and frame B we have the coil spring 39^a as shown in Fig. 1; mounted on the lower end of arm 34 we have the curved spring support 41, carrying on its upper end and 20 mounted thereon, the friction button 42 adapted to contact with disk 40, and its proper position to be determined by the regulating screw 43 mounted in arm 34. In 25 our wiring plan shown in Fig. 4 we designate the source of electrical energy by I; from source I extends wire 44 to motor C, and from motor C we have wire 45 extending to rheostat D, and from rheostat D we have wire 46, extending to contact point 30, 30 also from I we have wire 47 extending to point 32.

In the operation of our device having placed a record upon the turn table 3 in proper position we move handle 21 to the 35 left causing spring support 29 to bring point 30 in contact with point 32 and by the same movement of handle 21, brake 22 is moved out of contact with turntable 3, and by the same movement of handle 21 by action 40 of spring 20, stop arm 16 is moved out of contact with tone arm of player, by the release of pawl 19 connecting with ratchet 24 and the revolution of the motor causes gear 11 to revolve and by frictional contact 45 with disk 4 causes the disk and turntable to revolve, and with it the record, and the tone arm in position with its needle upon the record, the corresponding record tones are produced. The tone arm moved by the needle 50 in the channel of the record finally reaches the end of the spacing, at which instant the tone arm contacts with pin 16^a and moving lever 16 in a counter clockwise direction, and with it link 18 which moves 55 pawl 19 out of engagement with ratchet 24 and coil spring 27 distending moves lever 21 in a counter clockwise direction until brake 22 stops turntable, at the same time the rod 26 pressing against button 29 separates the contact points 22 and 30, thus 60 breaking the circuit and stopping the motor; thus automatically the current is cut off and the motor stops for the replacement of a new record. Having put a new record on turntable 3, the handle 21 is again moved to 65

the left and the mechanical operation is repeated as before.

Having thus described our invention what we claim as new and for which we desire Letters Patent is as follows:

1. In an electrically operated phonograph, controlling means for automatically controlling the movement of the driving mechanism comprising a baseboard, a shaft mounted therein, a turntable on said shaft on upper side of board, an electric motor on under side of base board, pivotally supported, having a friction wheel on shaft resiliently engaging a horizontally revolving disk mounted on shaft of turntable, a governor having resilient contact with disk, a rheostat mounted below the board, a switch and brake mechanism mounted on the surface of the base board, comprising a pivotally operating brake stop contacting with turn table, a lug contacting with tone arm, a handle lever operatively connecting between brake stop and electrical control switch, an electrical conduit extending from source of power to motor, to rheostat and control switch, and means whereby the tone arm automatically moves the brake against the turntable simultaneously closing the operating switch and controlling the electrical power to the drive shaft.

2. In an electrically operated phonograph; a base board; a record turntable supported on the upper side thereof; a drive shaft extending vertically through the base board; a friction disk mounted on the drive shaft below the base board; a motor pivotally mounted below the base board and having a friction wheel on its shaft which contacts with the friction disk; means mounted on the base board for controlling the electrical power to turntable, and simultaneously applying brake.

3. In an electrically operated phonograph, a removable base board a record turntable on the upper side thereof mounted on a driving shaft extending upwardly through the base board; a friction disk mounted on the drive shaft; a governor having resilient contact with the disk, a rheostat mounted on the baseboard and means for operating the same; a motor mounted in the mechanism; a friction wheel on its shaft having resilient contact with the disk; a switch and brake control mechanism, capable of operative contact with the tone arm; a connection between the brake mechanism and the power controlling switch mechanism.

4. In an electrically operated phonograph driving mechanism, means for controlling the driving mechanism, comprising a housing support having mounted thereon a turntable, an electric motor; a disk mounted on the turntable shaft; a friction wheel on a motor shaft engaging the disk; a governor adjustably controlled in contact with disk; a

combined switch and brake mechanism; a rheostat; means thru which the tone arm of the phonograph actuates the combined brake and switch mechanism; and causes the brake

- 5 to contact with the turntable and simultaneously closes the switch breaking the electrical circuit; an electrical conduit extending

from the source of power to the motor, to the thermostat and to the switch mechanism.

In testimony whereof we have affixed our ¹⁰ signatures.

CHARLES VASTIK.
MICHAEL BROZOVICH.
